CORSET AND THE LIKE

George E. Hawes, Bridgeport, Conn.

Application October 30, 1943, Serial No. 508,301

12 Claims. (Cl. 2—35)

The present invention relates to an improvement in foundation garments, such as corsets or the like, and is an improvement over the invention disclosed in the patent to George E. Hawes, for Corset or the like, No. 1,837,865, granted December 22, 1931, reissued August 7, 1934, Reissue No. 19,264. In this patent there is disclosed a garment including front and back portions each consisting of separately formed upper and lower vertically offset overlapped telescoping parts and relatively wide elastic side portions interposed as laterally yieldable non-telescopic spacers between the front and back portions. According to the invention disclosed in this patent, the upper and lower parts of the front and back portions are adapted to maintain independently their positions on the body upon relative movement of the body below the waistline, whereby the overlapping portions have telescoping action to expand and contract the front and back portions when the surfaces of the front and back of the wearer are lengthened and shortened on assuming different postures, as for instance standing, sitting, and bending forwardly or backwardly. The upper and lower telescoping parts of the back of the garment, as disclosed in this patent, include vertically disposed stays extending substantially their full heights, so that relatively long portions of these stays extend along the overlapping parts, substantially to the lower edge of the upper part and the upper edge of the lower part. There is a tendency in the underneath overlapped portion of the lower part, where the stays are tightly confined beneath the overlapped portion of the upper part, for the overlapped portions to press against each other with considerable friction, as they move relatively to each other during the expansion and contraction action, and also for the ends of the stays to wear through the ends of the stay pockets.

It is an object of the present invention to provide a foundation garment structure having the advantages of the invention disclosed in this patent, and which at the same time has a more freely acting contraction and expansion movement in the back section of the garment without frictional pressure between the upper and lower relatively movable parts and upon the flesh of the wearer.

It is a further object to provide a garment wherein the contracting and expanding back structure is relatively smooth, and to this end it is proposed to provide upper and lower relatively movable parts disposed in the same plane,

each section being contiguously offset from the other and not overlapped as in the above referred to patent. It is further proposed to provide an upwardly arched slit between the upper and lower relatively movable parts substantially intersecting the waistline and having its ends anchored at each side below the waistline, to the end that the line of pull from back to front against the diaphragm is broken so that elongation of the garment may take place freely without strain on the diaphragm.

A further object is to provide a garment having a band portion underlying the adjacent marginal portions of the upper and lower back parts, and arranged so as to embrace the back of the wearer substantially at the waistline, whereby this band portion remains in a relatively fixed position as the wearer assumes various postures, thus providing a fixed protective surface between the flesh of the wearer and the movable upper and lower parts of the back section of the garment.

A further object is to provide a garment having a fixed back band portion substantially at the waistline, and wherein vertical stays are provided to sustain this band against wrinkling and vertical contraction, and to provide a smooth vertically extending surface over which the relatively movable upper and lower parts of the garment are adapted to move toward and away from each other as the wearer assumes different postures.

A further object is to provide a garment wherein the upper and lower relatively movable parts of the back section of the garment are provided with vertical stays, extending substantially their full heights, these stays being free from any superimposed overlapping portions of the garment, so that frictional pressure between the relatively movable parts and upon the flesh of the wearer is eliminated and the tendency for the ends of the stays to wear through the stay pockets is reduced to a minimum.

It is further proposed to provide a garment wherein the upper and lower parts of the back section are provided with stays extending substantially their full height and which cooperate with a fixed waist engaging band having fixed vertically arranged stays, so that the contractable and expandable garment back is provided with vertically extending stays for its full height, and at the same time the wearer is protected, through the interposition of the fixed band and its fixed stays between the wearer and the relatively movable upper and lower back parts,

against frictional pressure of the stays in the region of the waistline.

With the above and other objects in view an embodiment of the invention is shown in the accompanying drawing, and this embodiment will be hereinafter more fully described with reference thereto, and the invention will be finally pointed out in the claims.

In the drawing:

Fig. 1 is a side elevation of a garment, according to the illustrated exemplary embodiment of the invention, disposed in flattened relation, and with the upper end of the side fastening shown in open position.

Fig. 2 is a rear elevation of the garment, also shown in flattened relation, and with portions of the upper and lower back sections broken away.

Fig. 3 is a vertical sectional view, taken along the line 3—3 of Fig. 2, the garment being shown in the same flattened relation as illustrated in Fig. 1.

Fig. 4 is a side elevation, showing the garment as worn and with the wearer in standing posture.

Fig. 5 is a similar view showing the wearer in sitting posture.

Fig. 6 is a similar view showing the wearer in forward bending posture.

Similar reference characters indicate corresponding parts throughout the several figures of the drawing.

Referring to the drawing, the foundation garment, according to the illustrated exemplary embodiment of the invention, comprises a front section, preferably formed of a central panel 10 and side panels 11—11 of non-elastic material secured together along vertically extending seams 12—12, and to the upper edges of which are secured the lower edges of the brassière portions 13—13. Centrally of the lower edge of the central panel 10 there is provided a horizontally elastic triangular gusset insert 14.

Upon the underside of the front section, and extending from a point substantially in line with the lower edges of the brassière portions to a line substantially in line with the upper end of the gusset insert 14, there is provided a substantially rectangular shaped inner liner member 15, secured at its vertical edges along the seams 12 and unsecured along its upper and lower edges. At each side of its central vertical line and in inwardly spaced relation to the seams 12 the inner liner is provided with substantially vertically arranged stays 16—16 disposed in stay pockets 17—17.

The front section is connected along one vertical edge by a seam 18 with the side section at one side of the garment, and is connected at its other vertical edge to the other side section by suitable fastener means, as for instance the hook and eye strips 19 and 20 as illustrated, or by slide fasteners, lacings, or the like. The side sections each comprise an upper panel portion 21, formed of non-elastic material and extending from the upper edge of the garment to a point substantially midway between the lower edge of the brassière portion and the waistline, its lower transverse edge being connected by a seam 22 to the upper edge of a forwardly arranged strip portion 23, formed of non-elastic material, and to the upper edge of a horizontally elastic portion 24 secured along its forward vertical edge by a seam 25 to the edge of the strip portion 23. The side section at one side of the garment is secured to the front section by the seam 18, while the side section at the other side has the eye strip 20 of the hook

and eye fastener secured along its edge for cooperation with the hook strip 19.

The back section of the garment comprises an upper part 26, preferably formed of a central and two side portions secured together along vertical seams 27—27, its substantially vertical side edges being secured to the rearward edges of the side sections along seams 28—28. The central portion of the upper back part 26 is provided with a triangular horizontally elastic gusset insert 29 having its point end terminating short of the lower edge. The lower edge of the upper back part is arranged substantially in proximity to the waistline and is arched upwardly between its ends, which are anchored along the seams 28—28 at points below the waistline while the intermediate arch extends to or slightly above the waistline. A suitable binding 30 is secured over this arched lower edge.

The lower part 31 of the back section is preferably formed of a central and two side portions secured along vertical seams 32—32, the central portion being substantially wider than the central portion of the upper back part, so that the seams 32—32 are outwardly offset a substantial distance from the seams 27—27 of the upper part. The side edges of the lower section are secured to the side sections by the seams 28—28, which extend continuously from the upper to the lower edge of the garment. The upper edge of the lower back part 31 is arched to conform to the lower edge of the upper part, its ends being anchored along the seams 28—28 at substantially the same points, and normally abuts this lower edge in the standing posture of the wearer. A suitable binding 33 is secured over this arched upper edge.

Beneath the upper and lower back parts and in position to be engaged substantially along its medial line in line with the waistline of the wearer there is provided a band portion 34, secured at its side edges along the seams 28—28, the lower edge of this band portion being arched upwardly and normally arranged in substantially parallel downwardly spaced relation to the slit opening between the arched edges of the upper and lower back parts, while its upper edge is arched downwardly and is spaced upwardly at its center from the slit opening a substantially equal distance from the downward spacing of its lower edge.

Along each of the seams 28—28 there are provided double stays 35 and 36 disposed in stay pockets 37—37, and extending from the upper edge of the garment to a point approximately in line with the waistline. The upper back part is provided along each of its seams 27 with double stays 38 and 39 provided in stay pockets 40—40, and extending substantially the full height of this upper back part. Along each of the seams 32 of the lower back part 31 there are provided double stays 41 and 42 disposed in stay pockets 43—43, and extending substantially the full height of this part, these stays being outwardly offset from the stays of the upper back part. In substantially parallel relation between the two series of double stays 41 and 42 of the lower back part there are provided a pair of spaced parallel single stays 44—44 disposed in stay pockets 45—45, these single stays being inwardly offset at their upper ends from the double stays 38 and 39 of the upper back part.

The band portion 34 is provided at a point inwardly offset from the stays of both the upper and lower back sections with a pair of spaced parallel single stays 46—46 disposed in stay pockets

47—47, and which sustain this band portion against wrinkling and vertical contraction.

Shoulder straps 48 and garters 49 are secured respectively upon the upper and lower edges of the garment.

In the back section of the garment the disposition of the edges of the upper and lower parts, with the adjacent arched edges forming a dividing slit substantially in the region of the waistline, is such that upon elongation or shortening of the body when assuming different postures one part will not be pulled or pushed by the part of the body engaged by the other part, and as the upper and lower parts have free relative movement, without the frictional resistance that might be produced by the overlapping of one part with the other part, there is no restraining action whatever imposed by one part upon the other.

The waistline may be considered as a fixed or neutral region of the body upon assuming different postures, the lengthening and shortening of the body taking place above and below the waistline, and the arrangement of the band portion 34 across the waistline in such position that it also remains fixed or neutral upon lengthening and shortening of the body provides a fixed protective layer between the body and the contiguously adjacent portions of the upper and lower back parts in the region of the waistline, and over which these relatively movable upper and lower back parts may move as the wearer assumes different postures. Hence, there is no direct sliding friction between the relatively movable parts of the garment and the body of the wearer, the upper relatively movable back part moving upwardly and downwardly through its engagement with the back below the waistline upon elongation and shortening of the body, the contiguous portions of the upper and lower back parts above and below the slit, and which overlie the region of the waistline, sliding freely over the fixed band 34 interposed between these relatively movable contiguous portions and the fixed or neutral waistline surface of the body. As the upper and lower back parts do not overlap the back of the garment presents a smooth continuous surface, and there is no tendency to bulge or wrinkle such as is the case where one of the relatively movable parts overlaps the other, causing the latter to be compressed and restricted in its movement and producing not only frictional pressure upon the body surface but also impeding the lengthening and shortening action of the garment.

In this connection it is pointed out that no additional pressure on the diaphragm of the wearer is created as the wearer assumes different postures such as standing, sitting or bending, and which pressure always occurs with the usual corset constructions. This pressure is caused in these usual corset constructions by the pulling action of the anchored lower rear portion, resulting in a corresponding restricting action of the upper and front portion. This is overcome in the present garment by breaking the diagonal line of pull, which may be considered as extending from the upper front portion across the side of the wearer to the lower back portion of the corset, this breaking of the diagonal line being accomplished by providing separate relatively movable upper and lower back parts which are divided substantially along the waistline and in substantially the lat-

eral line of the diaphragm, and which are anchored at the ends of the slit between the upper and lower parts at points below the waistline. The arrangement allows the lower back part of the garment to expand freely without pressure on the diaphragm. This advantage is particularly enhanced in the present garment by the arrangement of the fixed back engaging band 34 disposed across the waistline and directly in lateral line with the inner liner 15 provided in the front section of the garment and engaging directly over the diaphragm, the combined action of the inner liner 15 and the band 34 connected by the elastic side sections of the garment, providing a yieldable body encircling supporting band affording substantial support for the diaphragm from the waistline at the back, this additional support substantially eliminating any tendency for the upper and lower parts of the back section to exert direct diagonal pull upon the diaphragm upon assuming different postures.

The arrangement of the stays in the band portion 34 is such that there is no tendency for this fixed portion of the garment to wrinkle or contract vertically, thus providing a firm and smooth support for the relatively movable portions of the upper and lower parts of the back section. The arrangement of the stays extending the full heights of the upper and lower parts, in combination with the offset stays provided in the fixed band 34, provide complete vertical stiffening to the garment and at the same time there is no tendency for the adjacent ends of the stays to exert frictional pressure between the upper and lower parts and upon the body. Furthermore by eliminating such frictional pressure vertical strain upon the stays is relieved and the usual tendency for the stays to wear and break through the ends of the stay pockets is minimized.

In Fig. 4 the garment is illustrated in the standing posture of the wearer, the arched edges of the upper and lower parts of the back sections being contiguously adjacent and these parts being disposed in the same plane.

Fig. 5 shows the wearer in sitting posture, the lengthening of the body below the waistline causing the lower back part which clings to the lower part of the body to move downwardly away from the upper back part. Upon resuming a standing posture the lower back part will move freely to the position shown in Fig. 4, the upper arched edge moving over the surface of the fixed band 34.

In Fig. 6 the wearer is shown in a forward bending posture, the back of the body being lengthened both above and below the waistline and causing both the upper and lower back parts to move respectively therewith, the arched edges of the upper and lower parts having free movement over the surface of the band 34. Upon resuming a standing posture the upper and lower back parts have free movement to the position illustrated in Fig. 4.

It will be understood that different arrangements of the band 34 may be resorted to while still obtaining some of the advantages of the invention and without departing from the principle and scope thereof. For instance such band may be provided exteriorly, or both interiorly and exteriorly.

I have illustrated and described a preferred and satisfactory embodiment of the invention, but it will be understood that changes may be made therein, within the spirit and scope thereof, as defined in the appended claims.

Having thus described my invention, what I claim and desire to secure by Letters Patent is:

1. In a foundation garment, a back section comprising an upper part adapted to engage the body above the waistline, and a lower part adapted to engage the body below the waistline, said upper and lower parts being vertically offset one with respect to the other to provide a transversely extending slit substantially at the waistline, and having their contiguous edges above and below said slit parallel to each other and substantially abutted in the standing posture of the wearer.

2. In a foundation garment, a back section comprising an upper part adapted to engage the body above the waistline, and a lower part adapted to engage the body below the waistline, said upper and lower parts being vertically offset one with respect to the other to provide a transversely extending slit substantially at the waistline, and having their contiguous edges above and below said slit parallel to each other and substantially abutted in the standing posture of the wearer, the ends of said contiguous edges being fixed relatively to each other at points below the waistline.

3. In a foundation garment, a back section comprising an upper part adapted to engage the body above the waistline, and a lower part adapted to engage the body below the waistline, said upper and lower parts being vertically offset one with respect to the other to provide a transversely extending slit substantially at the waistline, and having their contiguous edges above and below said slit parallel to each other and substantially abutted in the standing posture of the wearer, the ends of said contiguous edges being fixed relatively to each other at points below the waistline, and said contiguous edges being arched upwardly between said fixed ends.

4. In a foundation garment, a back section comprising an upper part adapted to engage the body above the waistline, a lower part adapted to engage the body below the waistline, said upper and lower parts being vertically offset one with respect to the other to provide a transversely extending slit substantially at the waistline, and a transversely extending band portion at the waistline having its upper transverse edge disposed between the upper and lower edges of said upper back part and its lower transverse edge disposed between the upper and lower edges of said lower back part.

5. In a foundation garment, a back section comprising an upper part adapted to engage the body above the waistline, a lower part adapted to engage the body below the waistline, said upper and lower parts being vertically offset one with respect to the other to provide a transversely extending slit substantially at the waistline, a transversely extending band portion at the waistline having its upper transverse edge disposed between the upper and lower edges of said upper back part and its lower transverse edge disposed between the upper and lower edges of said lower back part, vertically arranged stays in said upper and lower parts extending substantially their full heights, and vertically arranged stays in said band portion laterally offset from said stays of said upper and lower parts and extending at their ends above and below the contiguous ends of said stays of said upper and lower parts.

6. In a foundation garment, a back section comprising an upper part adapted to engage the body above the waistline, a lower part adapted to

engage the body below the waistline, said upper and lower parts being vertically offset one with respect to the other to provide a transversely extending slit substantially at the waistline, and a transversely extending band portion underlying said upper and lower parts at the waistline having its upper transverse edge disposed between the upper and lower edges of said upper back part and its lower transverse edge disposed between the upper and lower edges of said lower back part.

7. In a foundation garment, a back section comprising an upper part adapted to engage the body above the waistline, a lower part adapted to engage the body below the waistline, said upper and lower parts being vertically offset one with respect to the other to provide a transversely extending slit substantially at the waistline, and having their contiguous edges above and below said slit parallel to each other and substantially abutted in the standing posture of the wearer, the ends of said contiguous edges being fixed relatively to each other at points below the waistline, and said contiguous edges being arched upwardly between said fixed ends, and a transversely extending band portion underlying said upper and lower parts at the waistline having its upper transverse edge arched downwardly and disposed between the upper and lower edges of said upper back part and its lower transverse edge arched upwardly and disposed between the upper and lower edges of said lower back part.

8. A foundation garment comprising in combination, a front section, side sections secured along their vertical forward edges to the side edges of said front section, and a back section secured along its vertical edges to the vertical rearward edges of said side sections and comprising an upper part adapted to engage the body above the waistline, a lower part adapted to engage the body below the waistline, said upper and lower parts being vertically offset one with respect to the other to provide a transversely extending slit substantially at the waistline, and a transversely extending band portion at the waistline having its upper transverse edge disposed between the upper and lower edges of said upper back part and its lower transverse edge disposed between the upper and lower edges of said lower back part.

9. A foundation garment comprising in combination, a front section, side sections secured along their vertical forward edges to the side edges of said front section, and a back section secured along its vertical edges to the vertical rearward edges of said side sections and comprising an upper part adapted to engage the body above the waistline, a lower part adapted to engage the body below the waistline, said upper and lower parts being vertically offset one with respect to the other to provide a transversely extending slit substantially at the waistline, and a transversely extending band portion underlying said upper and lower parts at the waistline secured at its vertical side edges to the vertical rearward edges of said side sections, having its upper transverse edge disposed between the upper and lower edges of said upper back part and its lower transverse edge disposed between the upper and lower edges of said lower back part.

10. A foundation garment comprising in combination, a front section, side sections secured along their vertical forward edges to the side edges of said front section, and a back section secured along its vertical edges to the vertical

rearward edges of said side sections and comprising an upper part adapted to engage the body above the waistline, a lower part adapted to engage the body below the waistline, said upper and lower parts being vertically offset one with respect to the other to provide a transversely extending slit substantially at the waistline, and a transversely extending band portion underlying said upper and lower parts at the waistline secured at its vertical side edges to the vertical rearward edges of said side sections, having its upper transverse edge arched downwardly and disposed between the upper and lower edges of said upper back part and its lower transverse edge arched upwardly and disposed between the upper and lower edges of said lower back part.

11. A foundation garment comprising in combination, a front section, an interliner within said front section secured at its vertical edges and unsecured at its upper and lower transverse edges and adapted to engage over the diaphragm of the wearer, side sections secured along their vertical forward edges to the side edges of said front section, and a back section secured along its vertical edges to the vertical rearward edges of said side sections and comprising an upper part adapted to engage the body above the waistline, a lower part adapted to engage the body below the waistline, said upper and lower parts being vertically offset one with respect to the other to provide a transversely extending slit substantially

5 at the waistline, and a transversely extending band portion at the waistline having its upper transverse edge disposed between the upper and lower edges of said upper back part and its lower transverse edge disposed between the upper and lower edges of said lower back part.

12. A foundation garment comprising in combination, a front section, an interliner within said front section secured at its vertical edges and unsecured at its upper and lower transverse edges and adapted to engage over the diaphragm of the wearer, side sections secured along their vertical forward edges to the side edges of said front section, and a back section secured along its vertical edges to the vertical rearward edges of said side sections and comprising an upper part adapted to engage the body above the waistline, a lower part adapted to engage the body below the waistline, said upper and lower parts being vertically offset one with respect to the other to provide a transversely extending slit substantially at the waistline, and having their contiguous edges above and below said slit arched upwardly and anchored at each end at points below the waistline, and a transversely extending band portion at the waistline having its upper transverse edge disposed between the upper and lower edges of said upper back part and its lower transverse edge disposed between the upper and lower edges of said lower back part.
